UNITED STATES PATENT OFFICE.

CHARLES M. ABBOTT, OF WATERTOWN, MASSACHUSETTS, ASSIGNOR TO SAMUEL CABOT, INC., OF BOSTON, MASSACHUSETTS, A CORPORATION OF MASSACHUSETTS.

INSULATING MATERIAL.

1,172,244.

Specification of Letters Patent. Patented Feb. 22, 1916.

Application filed April 6, 1911. Serial No. 619,253.

To all whom it may concern:

Be it known that I, CHARLES M. ABBOTT, a citizen of the United States, residing at Watertown, county of Middlesex, Commonwealth of Massachusetts, have invented certain new and useful Improvements in Insulating Materials, of which the following is a specification.

This invention relates to insulating materials, and particularly to an insulating strip comprising external layers or sheets with an interposed body of filling material within which insulating air spaces are formed.

I prefer for the manufacture of my material the use of a paper with an interposed body of such material as dried eel grass, the paper and eel grass being stitched to hold them together. For convenience in handling, this material is formed in webs or rolls with the stitching running longitudinally thereof. To meet ordinary commercial requirements two widths are needed, but, I have found by a certain arrangement of the strip that I am enabled to produce a single standard size strip which may be varied into the smaller size strip in the manner and for the purposes hereinafter explained. I have, furthermore, discovered that by the proportionment of the covering paper to the filling material used I am able to secure a substantially noncombustible insulation. I, furthermore, find that I am able to secure a proper proportionment through the use of a certain kind of paper pulp, as will be more fully set forth.

As illustrative of my invention I have shewn in the drawings a form of my insulating material.

Throughout specification and drawings like reference numerals are employed to indicate corresponding parts, and in the drawings:—Figure 1 is a plan view of a fragment of my quilt, and Fig. 2 a transverse section of the same.

The insulating strip is formed of two strips of paper 1 and 2 with an interposed filling 3 of eel grass or other suitable material. These elements are stitched together by seams 4, 5 and 6. The seams 4 are run longitudinally close to the edges of the strip, and the seams 5 between the edge of the

strip and the small or medial line thereof. The seams 6 are stitched a short distance on each side from the medial line, which is indicated at 7.

When it is desired to use the material between joists the strip may be longitudinally split along the line 7, thus forming two strips each stitched along its outside edge.

The material is usually made in a 36" width so that when split two strips 18" wide will be secured, thus allowing for the 14" space between joists with a 2" margin for fastening.

The sheets 1 and 2 are made from sulfate of soda paper pulp. I have found that by using paper made from this pulp I am able to keep the weight of the paper down to about 12% of the weight of the total insulating material. This amount of paper, even though it be in itself combustible, will not when combined with the eel grass afford sufficient ignition to burn the insulation. This is a great advantage as under these circumstances the insulation not only affords protection from heat and cold but is a practical fireproofing for ordinary purposes.

Various modifications may, of course, be made in the several elements of the article, all without departing from the spirit of my invention if within the limits of the appended claim.

What I, therefore, claim and desire to secure by Letters Patent is:—

As an article of manufacture, a substantially fire proof insulating strip comprising a pair of covering sheets manufactured from sulfate of soda paper stock and a filler of substantially non-combustible insulating material disposed therebetween, said covering sheets comprising substantially twelve per cent. of the total weight of the strip and combining with the substantially non-combustible filler to prevent ignition of the strip.

In testimony whereof, I affix my signature in presence of two witnesses.

CHARLES M. ABBOTT.
